FOREIGN PATENT DOCUMENTS

CN 307337594 * 5/2022

Primary Examiner — Paula Allen Greene(74) *Attorney, Agent, or Firm* — Michael Petrin; ATBP PC(57) **CLAIM**

I claim the ornamental design for an earphone holder, as shown and described.

DESCRIPTION

FIG. 1 is a front perspective view of an earphone holder, showing my new design;

FIG. 2 is a back perspective view thereof;

FIG. 3 is a top side view thereof;

FIG. 4 is a bottom side view thereof;

FIG. 5 is a right side view thereof;

FIG. 6 is a left side view thereof;

FIG. 7 is a front side view thereof;

FIG. 8 is a back side view thereof; and

FIG. 9 is a front perspective view thereof;

FIG. 10 is a back perspective view thereof;

FIG. 11 is a top side view thereof;

FIG. 12 is a bottom side view thereof;

FIG. 13 is a right side view thereof;

FIG. 14 is a left side view thereof;

FIG. 15 is a front side view thereof; and,

FIG. 16 is a back side view thereof.

The broken lines depict portions of the earphone holder in FIGS. 1 through 8 that form no part of the claimed design.
